MECHANICAL MOVEMENT

Werner Nowka, Garden City, N. Y., assignor to
Varispeed Corporation, Dover, Del.

Application July 24, 1943, Serial No. 496,002

19 Claims. (Cl. 74—63)

This invention relates to mechanical movements for application to power transmissions, and more particularly to variable speed transmissions.

This invention is based upon a variation and extension of the fundamental principle embodied in my prior patent for Mechanical movement, No. 2,322,539, granted June 22, 1943.

The principal object of the invention resides in a mechanical movement for transmitting rotary motion from a driving element to a driven element by means of a driving element which is so shaped as to form an angle with respect to the direction of its forward rotary movement and which functions to displace a driven element whose rotary movement is determined by guiding means, in the direction of such guiding means by a distance depending upon the relationship of the driving angle and the said direction of the guiding means.

Another object of the invention is to provide a mechanical movement for use in variable speed transmission, wherein a driving element is mounted on a drive shaft for rotation at a constant speed in such manner as to form an angle with the direction of rotation for rotating a driven element which is so-shaped or mounted as to allow its movement only in a fixed direction, and forward in such fixed direction at a speed depending upon the relationship of the driving angle and the said direction of driven movement.

Other novel features of the invention will become apparent as the specification is read in conjunction with the accompanying drawings, in which,

Figures 1, 2, and 3 are diagrammatic views illustrating the fundamental principle embodied in the present invention.

Figure 4 is a side elevational view of mechanical equivalents of the elements indicated in Figure 1.

Figure 5 is a horizontal sectional view on the line 5—5 of Figure 4.

Figure 6 is a side elevational view of other mechanical equivalents of the elements shown in Figure 1.

Figure 7 is a side elevational view of mechanical equivalents of the elements indicated in Figure 2.

Figure 8 is a vertical longitudinal sectional view of a variable speed transmission embodying the principle of my mechanical movement.

Figure 9 is a detail vertical sectional view on the line 9—9 of Figure 8.

Figure 10 is a detail sectional view illustrating the driven element in a tilted driven position.

Figure 11 is a vertical transverse sectional view on the line 11—11 of Figure 8.

Figure 12 is a detail side elevational view of the driven element per se.

Figure 13 is a side elevational view partly in section of a further modified form of mechanical speed transmission embodying the principle of my invention.

5 Figure 14 is a detail horizontal sectional view on the line 14—14 of Figure 13.

Figure 15 is a vertical transverse sectional view on the line 15—15 of Figure 13.

10 Figure 16 is a side elevational view of the reaction rings shown in Figure 13.

Figure 17 is a diagrammatic view similar to Figure 1, but showing position and direction of the driving element reversed from that shown therein.

15 Figure 18 is a diagrammatic plan view of the spherical shaped body in flattened condition when turning in clockwise direction.

Figure 19 is a view similar to Figure 18 but showing the position of the parts when the body is turning in a counterclockwise direction.

20 Referring to the drawings by reference characters, and at present to the diagrammatic view shown in Figure 1, the numeral 1 designates a triangular shaped driving element moving forward under the influence of a propelling force in the direction of the arrow F. A triangular shaped driven element 2, which in this instance is intended for sliding movement, although in practical use, the movement is rotatable as will be hereinafter shown and described. The driven element 2 is disposed in sliding contact with the inclined surface of the driving element 1 which forms an angle A with the direction of driving movement F. The angle A is defined as the driving angle and will be referred to as such hereinafter.

25 The driven element 2 is also provided with an inclined surface, forming a contact angle C with the inclined surface of the driving element 1, corresponding to angle B if referred to the direction of the driving movement F. The angle B is defined as the driven angle and will be so referred to hereinafter.

30 The angular surface of the driven element 2 is in operating contact with a third essential element of the movement, namely, a reaction element, herein shown as a roller 3.

35 By reference to Figure 1, it will be seen that as the driving element 1 moves forward a distance designated d to the position indicated in dotted lines, the driven element 2 rolls forward against the reaction element 3 in a direction determined by driven angle B to the position shown in dotted lines. The total forward movement of the driven element 2 in the driving direction F is therefore the distance d', which depends upon the driving distance d and the relationship of the driving

angle A and the driven angle B. Therefore, for any distance d of the forward movement of the driving element 1, the resulting forward movement d' of the driven element 2 becomes variable, if either the driving angle A or the driven angle B becomes variable.

Figure 2 of the drawings illustrates a slight variation of the principle set forth in Figure 1. In Figure 2, the reference character 1^a represents a driving element moving forward in the direction of the arrow F' and forms the driving angle A' with the said driving direction as in the diagram shown in Figure 1. The driven element is designated 2^a, and in this instance it constitutes a roller, while the reaction element 3^a forms the angle B' or what is termed the driven angle with the direction of driving movement F'. As related to the driving angle A' and driven angle B' as defined, the forward movement d^a of the driven element 2^a resulting from the forward movement d^a of driving element 1^a, is the same as in Figure 1 except that in Figure 1 the driven angle B is the difference between the contact angle C and the driving angle A or (B equals C-A), and therefore becomes variable if the driving angle becomes variable, while in Figure 2 the driven angle B' is fixed in the reaction element 3^a and therefore remains constant in all changes of the driving angle A'.

Figure 3 is a diagrammatic view illustrating the actual relationship of the resulting forward movement of the driven element to both the driving and driven angles of the diagrammatic showings in Figures 1 and 2. In Figure 3, A³ is the driving angle corresponding to the angles A and A' in Figure 1 and Figure 2 respectively, and B³ is the driven angle, resulting from the difference of contact angle C³ and driving angle A³ equivalent to the driven angle B in Figure 1 or formed by construction equivalent to the driven angle B' in Figure 2. Any point P on the inclined surface of the driving element 1^B is chosen and shown moved forward along the leg of the driven angle B³ to the position P' due to the forward movement d^3 of the driving element 1^B to the position shown in dotted lines. A parallel to the direction of driving movement through point P' intersects the leg of the driving angle A³ in point O. From the resulting triangle O, P, P', the displacement P, P', along the leg of the driven angle is seen to be:

$$P - P' \text{ equals } \frac{d^3 \times \sin A^3}{\sin (A^3 + B^3)}$$

The projection of the displacement $P - P'$ upon the direction of driving movement, which is the required resulting forward movement d^r , then is:

$$d^r \text{ equals } P - P' \times \cos B^3$$

$$\text{equals } \frac{d^3 \times \sin A^3 \times \cos B^3}{\sin (A^3 + B^3)}$$

$$\text{equals } \frac{d^3 \times \sin A^3 \times \cos B^3}{\sin A^3 \times \cos B^3 + \cos A^3 \sin B^3}$$

$$\text{equals } \frac{d^3 \times \sin A^3 \times \cos B^3}{\sin A^3 \times \cos B^3 (1 + \frac{\cos A^3 \times \sin B^3}{\sin A^3 \times \cos B^3})}$$

$$\text{equals } \frac{d^3}{1 + \frac{\cos A^3 \times \sin B^3}{\sin A^3 \times \cos B^3}}$$

$$\text{equals } \frac{d^3}{1 + \cot A^3 \times \operatorname{tg} B^3}$$

From the foregoing analysis of the movement employed in the present invention, it is appar-

ent that, while the forward movement of the driven element in the direction of the driving movement depends upon the relationship of both, the driving angle and the driven angle, it results from the fact that the primary displacement or the actual movement of the driven element occurs in the direction solely determined by the driven angle as defined, whether dependent on the driving angle as in Figure 1 or independent of the driving angle as in Figure 2. In other words, the driven angle serves as a guide for the resulting forward movement of the driven element and may therefore be properly called a guide angle. This function of the driven angle as guide angle is especially emphasized at this time because it forms an extremely important feature of the new mechanical movement employed in the present invention as will be more clearly understood hereinafter.

By reference to Figures 4 to 7 inclusive, it will be seen that I have embodied in mechanical equivalents, the fundamental elements which are diagrammatically illustrated in Figures 1 and 2. The mechanical elements thereby illustrated in Figures 4 to 7 are not intended to show the application of these principles in a continued drive, but merely to show mechanical elements embodying the fundamentals of the motion itself.

In Figures 4 and 5, the inclined surface of the driving element 1 of Figure 1 constitutes the disk 1^c which is fixed to one end of a drive shaft 4 so as to form an angle A⁴ with its direction of rotation F⁴ corresponding to the driving angle A in Figure 1. The driven element 2 of Figure 1 is represented by the driven element 2^c in Figures 4 and 5 and which consists of an annular ring-like body mounted for universal movement by a ball joint 5 upon the end of a driven shaft 6, the latter being mounted in co-axial relation to the driving shaft 4. The driven element 2^c is provided with an arcuate slot 7 forming a contact angle C⁴ with the inclined surface of the disk 1^c, resulting in the driven or guide angle B⁴ with reference to the direction of rotation F⁴. The third essential element for the functioning of this improved mechanical movement, namely, the reaction element 3 referred to in Figure 1 is here identified as a roller 3^c in cooperating contact with the arcuate or inclined slot 7 and which roller is rotatably mounted on the inner end of a stud 8. It is evident that this arrangement of mechanical parts exactly corresponds to the elements diagrammatically illustrated in Figure 1 and that, if the drive shaft 4 with its angular driving element 1^c rotates in the direction shown (clockwise) the driven element 2^c rotates forward in the direction determined by the guide angle B⁴ against roller 3^c in precisely the manner described in connection with Figure 1 and Figure 3.

Figure 6 illustrates a mechanical movement which is identical to that shown in Figures 4 and 5, except that the guide angle B⁶ is created by providing a stud 9 on the driven element 2^d, there being an eccentric 10 mounted on the stud 9 which has its periphery in contact with a reaction surface 3^d. The angle B⁶ in this instance is formed by one-half of the circumference of the eccentric as the base and twice the eccentricity as the height. The driving element 1^c is the same as in Figures 4 and 5, forming the same driving angle A⁴ with the direction of rotation.

Figure 7 illustrates mechanical elements equivalent to the diagrammatic showing in Figure 2, wherein the driven or guide angle is provided in

the reaction element rather than in the driven element. The reaction element is designated 3* and has an arcuate slot 11 therein forming the guide angle B⁴ with the direction of rotation F⁶ of drive shaft 4. The driven element 2 is provided with a stud 12 carrying a roller 13, which roller is disposed within the slot 11 and rides against the side walls thereof. Thus, as the drive shaft 4 and driving element 1^c rotate, the roller 13 and driven element 2^c rotate in the direction determined by the guide angle B⁴ exactly in the manner shown diagrammatically in Figure 2.

Having shown and described the mechanical elements embodying the fundamental principles involved in my improved mechanical movement, the said movement may be briefly defined as follows:

A driving element so shaped as to form an angle with the direction of its forward movement, displaces a driven element, whose movement is determined by a guiding means, in a direction of such guiding means by a distance depending upon the relationship of the driving angle and the said direction of said guiding means.

The movement may also be defined in the following terms:

A driving element mounted on a drive shaft rotating at constant speed, in such manner as to form an angle with the direction of rotation, rotates a driven element so shaped or mounted as to allow its movement only in a fixed direction, forward in such fixed direction, at a speed depending upon the relationship of the driving angle and the said direction of driven movement.

It is also apparent that this improved mechanical movement may be defined in terms of force as well as in terms of motion as has been done before. To illustrate, reference is again made to Figure 1 of the drawings wherein the driving element 1 is now considered as a wedge moving forward in the direction of the arrow F with a primary or driving force. Thus, it is apparent that this driving force exerts a greatly multiplied applied force upon the driven element 2 in a direction indicated by the arrow P, or a general axial direction when referring to the rotating mechanical elements shown in Figure 4, and the magnitude of this applied force is determined by the angularity of the driving or wedge angle. Therefore, the movement may also be defined as follows:

A drive force rotating a driving element so shaped or so placed as to create an applied axial force, displaces a driven element in a direction determined by guide means at a speed depending upon the relationship between the direction of the guide means and the said applied axial force.

It only remains to show how the movement hereinbefore defined may be incorporated into a mechanical power transmission device with variable speed. However, before going into a detailed description of a complete device based on the aforesaid fundamental principles together with other novel features and improvements, additional explanation is believed to be in order.

Figures 4 to 7 inclusive illustrate the essential mechanical elements of the invention, wherein the driven element is shown mounted on a ball joint or its equivalent, which means that the driven element is so mounted that it is free to rotate about a point rather than about an axis, and therefore, not only in one direction, but in all directions. The driven element, then, is free to undergo a movement so closely resembling that

of nutation that it is likely to be confused therewith. It is important at this point to stress the fact that the movement of the driven element constituting the essence of this invention, even if thus mounted on a ball joint, is not that of nutation, but an entirely new movement resulting from the displacement of a driven element in a direction forced by guiding means as has been clearly set forth hereinbefore. This recent statement of the invention is believed essential, in view of the fact that nutation has been used before as a base for speed variation, notably by C. W. Weiss, in his U. S. Letters Patent No. 1,146,982 dated July 20, 1915, and which is entirely based upon the transformation or translation of nutation into rotation, and wherein the variation of speed is obtained by changing the angle of the axis of a purely nutating body.

The structural, as well as the fundamental difference between nutation transformed into rotation, and the new mechanical movement of the present invention having thus been clearly established, it only remains to show the incorporation of the principle of the improved mechanical movement in a power transmission with variable speed, which is so shown in Figures 8 to 12 inclusive, wherein a complete variable speed transmission is shown embodying the above defined principles, and in which the guiding means are provided in the driven element, while in Figures 13 to 16, these same principles are shown incorporated in a construction wherein the guide means are provided in the reaction means, as will appear in full detail in the following description.

The numeral 21 (Figures 8, 9, and 10) shows a drive shaft mounted conveniently in bearings 22 and which may be connected with any source of rotating power and has one of its ends provided with a head 23 which is provided with a circular groove 24. A correspondingly shaped driving element 25 is slidably mounted in the groove 24. Means is provided for controlling the position of the driving element 25 relative to the plane of rotation of the driving shaft 21. Such means includes a link 26 which has one of its ends pivoted in a slot 20 provided in the driving element 25 and its other end pivotally connected to one end of a member 27 which is slidably mounted in a groove 28 axially provided on the drive shaft 21 and its head 23. The slide member 27 is provided with a recess 29 which receives the inner race of a bearing ring 30, the outer race of which is mounted in a circular recess 31 provided in a yoke-shaped member 32. The member 32 is drilled and tapped to fit the threaded portion 32' of a shaft 33 rotatably mounted in a housing 34 and which shaft 33 is in parallel relation to the drive shaft 21. This arrangement is more clearly seen in Figure 9, showing these parts in section and elevation. Fixed to the threaded shaft 33 is a bevel gear 35 which has constant meshing engagement with a companion bevel gear 35^a fixedly mounted on the inner end of a shaft 36. The shaft 36 is journaled in a bearing provided in the housing 34 and the outer end thereof has a hand-wheel 37 fixed thereto. By the manual turning of the hand wheel 37, axial movement is imparted to the member 32, and thereby to the bearing 30 and slide member 27.

In Figure 8 of the drawings, the initial position of the control means or control mechanism is shown, in which the face of the driving element 25 is parallel to the plane of rotation thereof. However, it is apparent that as the hand-wheel 37 is turned, the threaded shaft 33

is rotated, and thereby the member 32 and bearing 30 are gradually moved forward in the direction of the drive shaft 21, thereby displacing the driving element 25 through the link 26 into the angular position shown in Figure 10. Thus it will be understood that the aforesaid parts and their operation constitute a means for varying the angularity of the driving element 25 with respect to the direction of rotation of the drive shaft 21.

For creating an operating contact between the driving element 25 and a conveniently shaped driven element 38, I provide an annular seat 39 on the face of the driving element 25 and a complementary seat 40 on the confronting portion of the driven element 38 to receive a radial thrust bearing 41. The driving element 25 and the driven element 38 are thus in continuous rolling contact, and it is the angularity of this contact which constitutes the driving angle as formerly defined, and by reason of the link 26 and its operating mechanism, the driving angle, and thereby the speed of the driven element may be made variable.

In order to insure a continuous forward rotation of the driven element 38 in a fixed direction, the necessary guiding means must be provided. The guiding means in this instance embodies an annular series of equidistantly spaced overlapping arcuate grooves 42 provided in the outer peripheral surface of the driven element 38, and forming an angle with the face of the drive member 25 corresponding to the contact angle C of Figure 1, which grooves correspond in function to the arcuate slot 7 shown in Figure 4, and which may be more clearly seen in Figure 12, in which the said driven element 38 is shown independently. The series of arcuate grooves 42 respectively cooperate with balls 43, which balls not only contact the walls of the grooves 42 but also the walls of a corresponding groove 44 provided in the inner peripheral wall of a fixed ring 45 in the plane of rotation of the drive shaft 21 and concentric therewith.

To prevent any back-slip of the balls 43, each is placed within a clutch arrangement which in this instance is shown as a gliding plate 46 formed with an inclined recess 47 and a roller 48 seated in the recess and contacting the inner peripheral wall of the fixed ring 45, the cross section in Figure 11 showing this arrangement more clearly. Thus it will be understood that as the drive shaft 21 rotates, no movement will be imparted to the driven element 38 as long as the latter remains in its initial position, that is, with the contact bearing 41 parallel to the plane of rotation. However, as the position of the drive element 25 is changed in the manner hereinbefore described, a driving angle is formed, whereupon the driven element 38 is forced against one of the series of balls 43, which ball then becomes the operating ball. As long as the driving force and consequent applied force is acting against this particular operating ball, the latter is held stationary by its associated clutch device and the driven element 38 is rotated forward in the direction determined by the angularity of the groove 42 in conjunction with the angularity of the driving angle or the applied axial force generated by the wedge action due to the inclination of the drive member 25. During the operation of one ball 43, the other balls are taken along in forward rotation in the groove 44 of the fixed ring 45 by the driven element 38. As the driving angle advances during the continued rotation of the drive shaft 21, the applied force acts against the next

succeeding ball 43, which then becomes the operating ball until all balls have operated during one complete revolution of the drive shaft 21. By reason of the aforesaid construction and operation, one ball after the other in circumferential succession serves as a reaction element for its respective groove 42, which results in imparting a continued forward rotation to the driven element 38, a rotation made variable by the variation of the driving angle as previously explained.

In order to impart the forward rotation of the driven element 38 in the thus guided direction to the driven shaft 49, a flexible coupling between the driven element 38 and the driven shaft 49 is provided in the following manner. The driven shaft 49 is rotatably mounted in bearings 50 provided in one end of the housing 34 and co-axially disposed with respect to drive shaft 21. The driven element 38 is mounted on the driven shaft 49 by means of an intermediate ring 51 which is connected to the inner end of the driven shaft 49 by a pair of alined pins 52, while the ring 51 supports the driven element 38 by means of a pair of alined pins 53, the axis of the latter pins being disposed at right angle to the axis of the pins 52 as best illustrated in Figure 11.

In Figures 13 to 16 inclusive I have shown an alternate construction of my invention which in all essentials is identical to that shown in Figures 8 to 12 inclusive, except that the guide means is provided in the reaction elements rather than the driven element, as will appear further on. In the description and drawings, corresponding parts will be referred to by like reference characters. The said guide means which determines the direction and speed of rotation of the driven element, is in this case provided with two rings 101 and 102, the ring 102 being within the ring 101, both of which are rotatably mounted in the housing 34^a by eccentric rollers 104 which travel in annular grooves 105 provided in the housing 34^a. Each ring 101 and 102 is provided with a pair of opposite inclined slots, those of the outer ring 101 being designated 106 and those of the inner ring 102 being designated 107. The inclination of the slots 106 in the outer ring is opposite to that of the slots 107 in the inner ring so that they assume a crossing relation. In Figure 16 the relationship of these slots is shown in an elevation of these two rings.

The driven element 38^a is mounted on the driven shaft 49 by means of a flexible coupling as shown in Figure 8, and is in operative engagement with the driving element 25 which is adjustably mounted on the drive shaft 21 as herebefore explained.

The driven element 38^a is provided with a pair of opposed radially disposed pins 108, each of which carries rollers 109 and 110 which are respectively disposed in the slots 106 and 107 for rolling contact with the inclined side walls thereof.

The operation of the form of the invention shown in Figures 13 to 16 is similar to that shown in the previous construction, for as the drive shaft 21 rotates with the driving element 38^a in its initial position as shown in Figure 13, no axial force is exerted on the driven element, and therefore, there is no rotation of the driven element. However, when the driven element 38^a is given an inclination, a driving angle is created which transmits an axial wedge force from the driving element 25 to the driven element 38^a which forces the rollers 109 and 110 against the inclined surfaces of the respective slots 106 and 107. It is apparent that as the driving element 25 con-

tinually rotates, the axial pressure of the rollers against the inclined surfaces of the slots derived from the axial force generated by the drive member is exerted alternately forward and backward. It is for this reason that the rings 101 and 102 are provided with the slots 106 and 107 respectively, whose inclination is opposite one another with respect to the direction of rotation of the driving element 25. The forward rotation of the driven element 38^a is therefore alternately forced in the direction of the slots 107 in the inner ring 102 and in the direction of the slots 106 in the outer ring 101, during one-half revolution of the drive shaft 21, and therefore, during one-half revolution, the pins 108 and thereby the driven element 38^a will be axially forced in one direction and the rollers 110 rolling forward along the inclined surface of the walls of the slots 107 of the inner ring 102. During this one-half revolution of the drive shaft, the inner ring 102 is stationary, while the rollers 109 engaging the inclined surfaces of the slots 106 of the outer ring 101, causing the outer ring 101 to rotate forwardly a corresponding distance. During the second half revolution of the drive shaft 21, the rollers 109 and 110 are axially forced in the opposite direction with the result that the outer ring 101 becomes stationary, while the rollers 109 move forward along the inclined surface of the slots 106 in the outer ring 101, while the inner rollers 110 force the inner ring 102 to rotate forwardly. Thus it will be understood that during the continuous rotation of the drive shaft 21 and driving element 25, the rings 101 and 102 alternately become active and inactive. Each ring during its active period becomes stationary and forms the guide means to force the direction of forward rotation of the driven element 38^a, and during its inactive period it moves along to be in place to again perform its operative function.

The eccentric rollers 104 act to prevent back slippage of the rings during their active periods and they act as clutches in a manner similar to that of the slide clutch plate 46 and rollers 48 of the previous embodiment of the invention.

In the foregoing, however, another important feature of this movement has not yet been brought out sufficiently clear, the fact namely, that the movement of the driven element can take place only in the direction determined by the guide means regardless of the direction of rotation of the driving element.

To explain and illustrate this feature reference is again made to Figure 1. It was shown that the resultant forward movement of the driven element 2 by distance d' is due not directly to the forward movement of the driving element 1 in the direction indicated by the arrow F, but rather indirectly to the applied force indicated by the arrow P, generated by the impelling force F, and in the direction shown at right angles to the inclined surface of driving element 1.

Referring to rotating elements such as in Figure 4, this is in a general direction of the axis of rotation.

Since, then, the forward movement of the driven element is due to the force P and not the force F, it is immaterial in what direction the force F is moving. The direction of the resulting driven movement must be the same.

Figure 17 illustrates the displacement of the driven element 2^a if the driving element 1^a moves in the direction F^a opposite the direction F as shown in Figure 1. All the elements shown in Figure 17 are the same as those shown in Figure

1, the only difference being the position and direction of movement of the driving element 1.

If the driving element 1^a moves from its initial position shown in full lines by the distance d^a to the position shown in dotted lines, a force in the direction at right angles to the inclined surface of the said driving element is again generated, shown by the arrow P^a or, if referred to rotating elements such as shown in Figure 4, again in the general direction of the axis of rotation.

This means that the driven element 2^a is forced against the reaction roller 3^a in the same general direction as the driven element 2 in Figure 1. The resultant forward movement of the said driven element 2^a against the reaction roller 3^a can therefore only occur in the direction indicated by the arrow R^a, determined by the relationship between the driving angle A^a and the driven angle B^a exactly as before. The driven element 2^a has thereby moved from its original position shown in full lines to that shown in dotted lines by the distance d^a , corresponding to the distance d, in Figure 1.

As applied to the complete unit as otherwise fully described above, this feature is more specifically illustrated in Figure 18 and Figure 19, to which reference is now made.

For the sake of greater clearness, the driven element, shown in the drawings in the form of a partly spherical shaped body 38, provided with the inclined grooves 42, is shown in Figure 18 and Figure 19 flattened out into the element 5^x, shown in its original position in full lines and provided with the inclined grooves 6.

Corresponding to the balls 43 in the drawings, the balls 1^x, 2^x, 3^x and 4^x are shown in Figures 18 and 19, fitting into grooves 6^x and by means of suitable clutch arrangements constrained to move only in the direction indicated by the arrow A^x.

The inclined surface provided on the driving element 25 in Figure 10 is in Figures 18 and 19 represented by the wedge 7^x, which has moved from some initial position into that shown in the figures, which are identical except that in Figure 18 the drive shaft rotates clockwise and therefore the wedge 7^x has moved from left to right as shown by arrow B^x, while in Figure 19 the drive shaft has rotated counterclockwise and therefore from right to left as shown by the arrow B^x.

As a result of this rotation the driven element 5^x has in both cases moved the distance d^x to the position shown in dotted lines in the direction indicated by the arrow C^x, that is, in the same direction A^x, in which the balls are constrained to move. The only difference is that in the clockwise rotation of the drive shaft illustrated in Figure 18, the balls have become and are becoming operative in the rotation 1^x, 2^x, 3^x, 4^x, in the manner clearly described in connection with the drawings, while in the counterclockwise rotation of the drive shaft illustrated in Figure 19 the balls have become and are becoming operative in the opposite rotation 4^x, 3^x, 2^x, 1^x.

The resulting forward rotation of the driven element, however, is the same, whether the drive shaft rotates clockwise or counterclockwise.

While I have shown and described what I consider to be the preferred embodiments of my invention, I wish it to be understood that such changes in construction and design as come within the scope of the appended claims may be re-

sorted to if desired without departing from the spirit of the invention.

Having thus described the invention, what I claim as new and desire to secure by Letters Patent of the United States, is:

1. A mechanical movement comprising, in combination, a drive shaft, a driving element mounted on said drive shaft, a driven shaft, a driven element mounted on said driven shaft, and guide means located in such position relative to said driving and driven elements to cooperate with the driving and driven elements to cause the driving element to impart to the said driven element a rotation determined by the said relative position of the guide means with respect to the driving element and driven element.

2. A mechanical movement comprising, in combination, a drive shaft, a driving element mounted on said drive shaft, a driven shaft, a driven element mounted on said driven shaft, means for transmitting a drive force from said driving element to said driven element in the direction of the axis of rotation of the drive shaft, and guide means so fashioned as to cooperate with the said driving element to impart to the said driven element a combined turning and axial movement.

3. A mechanical movement comprising in combination, a drive shaft, a driving element mounted on said drive shaft, an inclined surface provided on said driving element, a driven shaft, a driven element in operating contact with said inclined surface, and guide means cooperating with the inclined surface of the driving element and with the driven element for imparting to the driven element a combined turning and axial movement at a speed dependent upon the inclination of said inclined surface relative to said guide means.

4. A mechanical movement comprising, in combination, a drive shaft, a driven shaft, a reaction element co-axially disposed relative to the drive shaft and the driven shaft, a driving element mounted on said drive shaft, a driven element mounted on said driven shaft, means for transmitting a driving force from said driving element to said driven element in the direction of the axis of rotation of the drive shaft to cause an axial displacement of said driven element, guide means provided on said driven element to determine the direction of said axial displacement, and contact elements interposed between said driven element and said reaction element for imparting rotation to said driven element at a speed dependent upon the direction of axial driving force and of said axial displacement.

5. A mechanical movement comprising, in combination, a drive shaft, a driving element mounted on said drive shaft at an angle relative to the direction of rotation of the drive shaft and forming a driving angle, a driven shaft, a driven element mounted on said driven shaft and disposed in operative engagement with said driving element, and guide means so positioned relative to said driving element as to form a guide angle with respect to the direction of rotation of said drive shaft and disposed in cooperating contact with the driven element to impart a combined turning and axial movement to the driven element at a speed depending upon the relative angularity of the driving angle and the guide angle.

6. A mechanical movement comprising in combination, a drive shaft, a driving element mounted on said drive shaft, a driven shaft, a driven element mounted on said driven shaft, means for transmitting a drive force from said driving ele-

ment to said driven element in the direction of the axis of rotation of said drive shaft to cause an axial displacement of said driven element, guide means in cooperating engagement with said

5 driven element to determine the direction of said axial displacement for imparting rotation to said driven element, and means for transferring the rotation of the driven element to the driven shaft.

7. A mechanical movement comprising, in combination, a drive shaft, a driven shaft co-axial with the drive shaft, a driving element mounted on said drive shaft, a driven element in operative contact with said driving element, guide means in operative contact with said driven element and cooperating with said driving element to impart a compound movement of axial displacement and rotation thereto, and a flexible coupling between the driven element and the driven shaft to impart rotation to the driven shaft.

10 8. A mechanical movement comprising, in combination, a drive shaft, a driving element mounted on said drive shaft, means for transmitting a drive force from the driving element to the driven element in the same direction of the axis of rotation 20 of the drive shaft to impart axial movement to the driven element, guide means in operative contact with the driven element to convert the axial movement into a combined movement of axial displacement and rotation, and means to vary the 25 intensity of the axial drive force and consequently vary the speed of rotation of the driven element.

9. A mechanical movement comprising, in combination, a drive shaft, a driven shaft coaxial with the drive shaft, a driving element mounted on 30 the drive shaft at an angle relative to the direction of rotation of the drive shaft, a driven element, coupling means operatively connecting the driven shaft and driven element, a thrust bearing intermediate the driving element and the 35 driven element and with which confronting portions of the driven and driving elements engage to impart a driving force from the driving element to the driven element in the direction of the axis of rotation of the drive shaft to cause a displacement of the driven element, and guide means operatively associated with said driven element to determine the direction and consequently the 40 amount of said displacement.

10. A mechanical movement comprising, in combination, a drive shaft, a driven shaft co-axial with the drive shaft, an annular driven element normally co-axial with the drive and driven shafts, a flexible connection between said driven element and said driven shaft, a driving 50 element, confronting portions provided on the driven element and the driving element, bearing means between the confronting portions, means for mounting the driving element upon the drive shaft for movement from an inoperative position parallel to the direction of rotation of the drive shaft to varied operative positions in angular relation to the direction of rotation of the drive shaft to cause correspondingly varied displacement of the driven element, and guide means for determining the direction and thereby the 55 amount of such varied displacement.

11. A mechanical movement comprising, in combination, a drive shaft, a driven shaft, a reaction element co-axially disposed relative to the drive shaft and the driven shaft, a driving element mounted on said drive shaft, a driven element mounted on said driven shaft, means for transmitting a driving force from said driving element to said driven element in the direction 60 of the axis of rotation of the drive shaft to cause 65

an axial displacement of said driven element, said means including complementary seat portions on the driving and driven elements, a thrust bearing interposed between the driving and driven elements and being seated against said seat portions, guide means provided on said driven element to determine the direction of said axial displacement, and contact elements interposed between said driven element and said reaction element for imparting rotation to said driven element at a speed dependent upon the direction of axial driving force and of said axial displacement.

12. A mechanical movement comprising in combination, a drive shaft having an enlarged flat head at one end thereof, a driving element slidably mounted in the outer face of said head and being provided with a flat surface normally disposed parallel to the direction of rotation of the drive shaft, a driven shaft coaxial with the drive shaft having one of its ends disposed in relatively close spaced relation to said head, an annular driven element, a flexible connection between the driven element and the aforesaid end of the driven shaft, said driven element having a surface complementary to and confronting the outer surface of the head and spaced therefrom, a thrust bearing between the confronting surfaces of the driven element and the drive element and in bearing contact therewith, actuating means for sliding the drive element to a position with its outer flat surface disposed at an angle relative to the direction of rotation of the drive shaft and to correspondingly move the driven element relative to the driven shaft to provide a driving angle, guide means disposed relative to the driving element to form a guide angle with respect to the direction of rotation of the drive shaft to impart a combined turning and axial movement to the driven element at a speed depending upon the relative angularity of the driving angle and the guide angle.

13. A mechanical movement comprising in combination, a driven element suitably mounted, a driving element suitably mounted and in operating contact with the said driven element to impart to the said driven element a movement of oscillation, and guide means to translate this movement of oscillation into a compound movement of rotation and axial displacement in a direction determined by the relationship of the said guide means to the said driving element.

14. A mechanical movement comprising in combination a driven element suitably mounted, a driving element suitably mounted and in operating contact with the said driven element to impart to the said driven element a movement of axial displacement, and guide means in operating contact with the said driven element and cooperating with the said driving element to translate the said axial displacement into a compound movement of rotation about the axis of rotation of the said driving element and axial displacement in the direction and thereby by an amount and at a speed determined by the relationship of the said guide means and the said driving element.

15. A mechanical movement comprising in combination, a driven element suitably mounted, a driving element suitably mounted and in operat-

ing contact with the said driven element to impart to the said driven element a movement of oscillation, guide means in operating contact with the said driven element to convert the said movement of oscillation into a compound movement of axial displacement and rotation about the axis of rotation of the said driving element depending upon the said relationship of the said guide means and the said driven element, and means to vary the said relationship between the said guide means and the said driving element.

16. A mechanical movement comprising in combination, a driven element suitably mounted, a drive shaft rotating in constant direction, a driving element mounted on said drive shaft and in operating contact with the said driven element to impart to the said driven element a movement of oscillation, and guide means to convert the said movement of oscillation into a compound movement of axial displacement and rotation in a direction and by an amount solely determined by the relationship between the said driving element and the said driven element, the movement of rotation being about the axis and in the direction of rotation of the said drive shaft, as determined by said guide means.

17. A mechanical movement comprising in combination, a driven element suitably mounted, a drive shaft rotating in constant direction, a driving element mounted on the said drive shaft and in operating contact with the said driven element to impart to the said driven element a movement of oscillation, and guide means to convert the said movement of oscillation into a compound movement of axial displacement and rotation in a direction and by an amount determined by the relationship of the said guide means and the said driving element, the movement of rotation being about the axis but in a direction opposite to that of the said drive shaft, as determined by said guide means.

18. A mechanical movement comprising in combination, a driven element suitably mounted, a drive shaft rotating alternately in opposite directions, a driving element mounted on said drive shaft and in operating contact with the said driven element to impart to the said driven element a movement of oscillation, and means to convert this movement of oscillation into a compound movement of axial displacement and rotation, the rotation being about the axis of rotation of the said drive shaft, but constantly in one direction, determined by the said guide means.

19. A mechanical movement comprising in combination, a driven element suitably mounted, a drive shaft rotating alternately in opposite directions, a driving element mounted on said drive shaft and in operating contact with the said driven element to impart to the said driven element a movement of oscillation, and means to convert this movement of oscillation into a compound movement of axial displacement and rotation, the rotation being about the axis of rotation of the said drive shaft, but constantly in the direction determined by the said means, and means to vary the amount and therefore the speed of the said constantly one-directional rotation.

WERNER NOWKA.
